UNITED STATES PATENT OFFICE.

JAMES E. HITCHCOCK, OF FULLERTON, CALIFORNIA.

CASING HEAD.

Application filed August 20, 1923. Serial No. 658,333.

My invention relates to casing heads for closing the end of any pipe on which a collar or coupling is screwed, and is particularly useful in the oil well apparatus for closing the upper end of the oil well casing and connecting with a pump in order that cement may be pumped under pressure into the casing or mud circulated therein under pressure.

10 The general object of my invention is to provide a simple casing head of the character stated which may be readily applied to a collared end of a pipe or removed therefrom and which will be highly efficient in 15 operation.

Other objects and advantages will be made evident hereinafter.

Referring to the drawing which is for illustrative purposes only:

20 Fig. 1 is a side elevation of my casing head applied to a collar on the upper end of an oil well casing, means being shown for raising or lowering the casing and for holding the same in position for pumping cement or mud therethrough, and the casing being shown extending through the floor of an oil well derrick into an oil well.

Fig. 2 is an enlarged side elevation of my casing head shown applied to a collar on 30 the upper end of an oil well casing.

Fig. 3 is a vertical longitudinal section of my casing head applied to a collar on the upper end of an oil well casing taken on line 3—3 of Fig. 4.

35 Fig. 4 is a plan view of my casing head.

Fig. 5 is a horizontal section of my casing head and the casing to which my head is applied taken on line 5—5 of Fig. 3.

40 Fig. 6 is a side view of a modified form of one of the links of the clamping means of my invention.

My casing head includes a ring 1, cap 2, segmental slips 3 and clamping means 4. The internal diameter 5 of the ring 1 is 45 larger than the oil well casing 6 and the collar 7 screwed on the upper end of said casing so that said ring may be readily slipped over said collar and below the same around said casing. The upper inner edge 50 of the ring 1 is bevelled to form a conical seat 7, upon which the seat rests, conical segmental flanges 8 depending from the slips 3 respectively, the upper face of said slips being adapted to engage the lower edge of 55 the collar 7.

The cap 2 is provided with an annular groove 9 in its under side, to receive the upper edge of the collar 7, and is formed on said side with an annular flange 10 depending below and forming the inner wall of 60 said groove, there being a packing 11 in said groove for engaging the upper edge of said collar when introduced into said groove.

The clamping means 4 is constructed as follows: Radial arms 12, preferably four in number and spaced equi-distant apart, which project outwardly from the ring 1 and are provided with radial slots 13 in which are secured the lower ends of upstanding vertical links 14 by means of pins 15 extending horizontally through said arms and said lower ends of said links, the walls of said slots being shown as of such configuration as to hold said links substantially upright, to facilitate assembly. Radial arms 16, corresponding to the arms 12, project outwardly from the cap 2 and are provided with radial slots 17, through which extend the upper ends of the links 11. The upper ends of said links are provided with slots 18 to 80 receive wedges 19 which are adapted to engage the upper face of the cap 2 to draw the ring 1 upwardly until the upper faces of the slips 3 engage the lower edge of the collar 7, and to draw the cap 2 downwardly until the upper end of said collar seats in the groove 9 against the packing 11 and upon the outer face of the flange 10, whereby the head is clamped firmly upon the ends of said collar and an effective fluid-tight joint formed between the upper end of said collar and the head cap 2.

85 The cap 2 is provided with a central threaded aperture 20, in which aperture is screw seated one end of a pump pressure pipe 21, which end of said pipe is threaded for engaging the threads of said aperture, through which pipe 21 cement may be pumped under pressure through the casing into cavities in the well or mud circulated 100 through said casing under pressure, in a well known manner. The ring 1 is provided with a pair of eyes or apertured ears 22 to receive the lower ends of a U-shaped hanger 23, on the lower ends of which hangers are 105 screw seated nuts 24 which engage the lower side of said eyes so that a hook 25 on the lower end of a cable 26 suspended in an oil well derrick may engage the upper end of said hanger for lifting the casing 6 through 110

my closing head and holding said casing in position for pumping cement or mud under pressure therethrough.

In the modified form of the link 14 shown in Fig. 6, said link is made in two sections, 30 and 31, joined together by a screw shank 32 on the lower end of section 31, which shank seats in a threaded socket 33 in the upper end of section 30, the lower end of section 30 being provided with a pin hole 34 to receive a pin 15 to connect said section to an arm 12 of ring 1, and the upper end of section 31 having a slot 18 to receive a wedge 19. By turning the section 31 one way or the other, the threaded engagement of the shank 32 and socket 33 will cause the link 14 to be extended or shortened, whereby the ring 1 and cap 2 may be adjusted closer together or further apart to fit collars 7 of different lengths, thus adjusting the limits of clamping action of the clamping means 4.

I claim as my invention:

1. A casing head including: a cap; a ring applicable to a casing below a collar secured on an end of said casing; means applicable to said ring for engaging the lower end of said collar; upstanding links secured at their lower ends to said ring and projecting through slots in said cap; and wedges adapted to be driven through slots in the upper

ends of said links for engaging the upper face of said cap to clamp said ring and said cap upon the lower and upper ends respectively of said collar; said links being formed in two sections, a threaded shank on one end of one section engaging a threaded socket in the adjoining end of the other section for extending or shortening the links to vary the clamping of the head to adapt the head to the collars of different lengths. 40

2. A casing head including: a ring applicable to a casing below a collar secured on an end of said casing; means applicable to said ring for engaging the lower end of said collar; upstanding links secured at their lower ends to said ring and projecting through slots in said cap; and wedges adapted to be driven through slots in the upper ends of said links for engaging the upper face of said cap, to clamp said ring and said cap upon the lower and upper ends respectively of said collar; said links being formed in two sections provided with threaded means for extending or shortening said links to vary the clamping of the head. 55

In testimony whereof, I have hereunto set my hand at Los Angeles, California, this 13th day of August, 1923.

JAMES E. HITCHCOCK.
